UNITED STATES PATENT OFFICE.

JOSEPH B. LONG, OF CHICAGO, ILLINOIS.

DESIGN FOR A CADDY.

SPECIFICATION forming part of Design No. 33,527, dated November 6, 1900.

Application filed August 20, 1900. Serial No. 27,511. Term of patent 3½ years.

To all whom it may concern:

Be it known that I, JOSEPH B. LONG, a citizen of the United States, residing at Chicago, in the county of Cook and State of Illinois, 5 have invented and produced a new and original Design for Caddies, of which the following is a specification, reference being had to the accompanying drawings, which are made a part of said specification, and in which—
10 Figure 1 is a perspective view of a caddy embodying the new design. Fig. 2 is an end elevation thereof with the legs omitted.

The leading essential feature of the new design is the body, comprising the upper portion A and the lower portion A', projecting forward some distance beyond the upper portion A, said upper and lower portions having front panels B and B', respectively, each of which is curved in vertical planes, the top 15 of the lower projecting portion A' being inclined downward and forward.

Minor features of the design are sunken

panels C C' (said panels being, in fact, lids) in the inclined portion aforesaid and narrow raised strips or ribs D and D', disposed at the 25 upper margins of the panels B and B', respectively, and each having along its horizontal margin inturned flanges d.

Another minor feature of the design is the top, comprising the flat horizontal portion E 30 and the curved sunken panels F, (which are, in fact, lids,) disposed between the portion E and the raised rib D.

What I claim as new, and desire to secure by Letters Patent, is—

The design for a caddy substantially as herein shown and described.

Signed at Chicago, Illinois, this 30th day of July, 1900.

JOSEPH B. LONG.
